**ACTUATOR FOR LEVELER CONTROL
MECHANISM**

Raymond A. Gurries, San Jose, and John Curlett, Los Gatos, Calif., assignors to Gurries Manufacturing Co., San Jose, Calif., a corporation of California

Application September 17, 1957, Serial No. 684,481

6 Claims. (Cl. 37—180)

This invention relates to ground leveling machines, and particularly to the longitudinal-level controlled actuator for a leveler of the type shown in Patent No. 2,792,651, granted May 21, 1957, to H. W. Hobday.

The purpose and specific functioning of the actuator as shown in the patent above noted, is set forth in said patent. It was found that in operation, however, the actuator as constructed was subject to rapid wear, since all bearing points were exposed and could not easily be maintained in a properly lubricated condition. Also, the valve of the actuator assembly was a separate entity from the actuating mechanism, and could not well be made or enclosed as a unit therewith.

The principal object of the present invention is to improve and simplify the construction and operation of the actuator, and to arrange the operating parts so that they are all enclosed in compact unitary form in a dirt-proof and tamper-proof manner, and so that no adjustments are ever required, and proper lubrication ceases to be a problem.

Another object of the invention is to provide a valve unit for the actuator which comprises a proportional-porting servo valve actuated upon deviation of the leveler from a proper level, and a positive cam-operating lock valve, controlled by rotation of the tail boom of the leveler about a vertical axis.

This arrangement is an improvement over the single valve of the previous structure in that it allows a more sensitive control and movement of the servo valve to be obtained than was previously the case.

It is also an object of the invention to provide a practical, reliable, and durable actuator for level control mechanism, and one which will be exceedingly effective for the purpose for which it is designed.

These objects are accomplished by means of such structure and relative arrangement of parts as will fully appear by a perusal of the following specification and claims.

In the drawings:

Fig. 1 is a fragmentary side outline of a land leveler showing the same equipped with the improved actuator.

Fig. 2 is an enlarged sectional elevation of the actuator detached and showing the servo valve closed and the lock valve in its normal open position.

Fig. 3 is a fragmentary sectional plan on line 3—3 of Fig. 2.

Fig. 4 is a fragmentary sectional elevation, in the plane of Fig. 2, showing the lock valve control cam turned, and the valve in a locked position.

Referring now more particularly to the drawings, and to the characters of reference marked thereon, the leveler to which the improved actuator is applied comprises a main rigid frame structure 1, which—intermediate its ends—supports a blade and bowl unit 2. Transversely spaced wheels 3, mounted for vertical adjustment relative to the frame structure, are disposed just rearwardly of the unit 2; adjustment of the wheels being

accomplished by means of hydraulic rams 4, as shown and described in the aforementioned Patent No. 2,792,651.

A tail boom 5 projects rearwardly from the frame structure 1, being connected thereto, as at 6, for relative swivel movement in a vertical plane and for independent relative swivel movement in a horizontal plane and about a vertical axis, as at 7, as shown in said patent.

10 The rams 4 are actuated to relatively raise or lower the wheels 3 upon relative swivel movement of the tail boom 5 in a vertical plane, and are held inactive upon relative swivel movement of the tail boom in a horizontal plane a predetermined amount from a normal in-line position with the main frame, regardless of any accompanying swivel movement in a vertical plane.

The improved actuator by means of which the above recited ram action is obtained comprises a housing 8. This housing includes a lower main portion or member 9 which is rigidly secured on a bracket 10 supported on the frame structure 1 at its rear end and overhanging the tail boom connections, as shown in Fig. 1.

The housing 8 includes a top dome 11 seated on top of the housing portion 9, and swivelly mounted thereon, for rotation about a vertical axis on a neck 12 on the upper end of said main housing portion 9. The dome is held against removal from said portion 9 by a collar 13 secured thereon and engaging the base flange 14 of the dome.

30 Secured in the dome 11 concentric therewith, and depending therefrom inside the housing, is a shaft 15; the housing 8 being mounted on the bracket 10 so that said shaft is coaxial with the axis of horizontal swivel movement of the tail boom, as indicated in Fig. 1.

35 A sleeve 16 is slidable on the shaft, said sleeve adjacent its upper end being formed with a forwardly projecting horizontal slot 17. A cross pin 18 rides in this slot; said pin being mounted on the outer end of a yoke 19 which straddles the sleeve and is fixed on a transverse shaft 20 journaled in the dome 11 rearwardly of the sleeve 16.

40 A lever 21 projects rearwardly from and is secured on shaft 20. A push-pull rod 22 is connected to and depends from lever 21 and depends to operative connection with a bracket 23 on the tail boom, as shown in the aforementioned patent, in such a manner that when the tail boom swivels vertically, the lever 21 is raised or lowered, and when the tail boom swings horizontally the lever 21—and dome 11—are likewise swung horizontally or about a vertical axis.

45 The sleeve 16 at its lower end carries an enlarged flat head 24 whose under surface engages the upper end of an L-shaped rocker arm 25 turnably mounted intermediate its ends on a cross shaft 26 mounted in the lower housing portion 9. At its lower end the rocker arm is provided with a cross pin 27 which somewhat loosely rides in a vertical slot 28 formed in the adjacent end of the plunger or spool 29 of the servo valve unit of the actuator. This spool extends horizontally or at right angles to the shaft 15 and slides in a sleeve 30 secured in the housing member 9.

50 The sleeve 30 is formed on the outside with a pair of longitudinally spaced, circumferential grooves 31 and 32 with a similarly disposed central groove 33, and since the sleeve is surrounded by the metal of housing member 9, said grooves form in effect enclosed passages or chambers.

55 A plurality of relatively small, circumferentially and axially spaced ports 34 connect the groove chambers 31 and 32 with the interior of the sleeve 30. Ports or passages 35 and 36 lead through the housing member 9 from chambers 31 and 32, respectively, and are connected

to a pressure conduit 35a and to a relief conduit 36a, respectively. Larger ports 37 connect the interior of the sleeve 30 with the central chamber 33.

The spool 29 is formed with a pair of spaced lands 38 arranged when the spool is in a neutral position to cover all ports 34 while always leaving the ports 37 uncovered.

A somewhat heavy compression spring 39 extends lengthwise of spool 29, bearing at one end against the end of sleeve 30 furthest from the rocker arm 25, and at the other end against a retainer 40 mounted on a stem 41 rigid with, and projecting from, the adjacent end of the spool 29.

Above the servo valve and parallel to the spool 29 is the spool 42 of the lock valve; said spool being slidable in a sleeve 43 fitted in, and mainly surrounded by, the metal of the housing member 9.

The sleeve is formed on the outside with circumferential longitudinally spaced grooves 44 and 45 which form enclosed chambers. Ports 46 and 47 provide communication between chambers 44 and 45, respectively, and the interior of the sleeve.

A passage 48 leads from chamber 44 to the exterior of the housing member 9 for connection to a branched conduit (not shown) leading to and from the rams 4, while a passage 49 connects chambers 45 and 33. The spool 42 includes a land 50 arranged in one position of the spool to uncover the ports 47, as shown in Fig. 2, and another position of said spool to cover or close said ports, as shown in Fig. 4. In either position of the spool 30 the ports 46 remain open or uncovered.

Secured on the shaft 15 in horizontal alinement with the spool 42 is a cam disc 51 engaged on its periphery by a sleeve-guided ball 52 which also engages the adjacent end of said spool; said spool extending radially of the shaft 15.

A compression spring 53 engages the opposite end of the spool 42 and acts to hold the ball in engagement with the spool and cam disc. The cam disc is formed on its periphery with a wide-angle V-notch 54, as shown in Fig. 3, in which the ball 52 seats under normal operating conditions, or when the tail boom and the main frame of the leveler are in straight longitudinal alinement. Under such conditions the ports 47 are uncovered or open, as shown in Fig. 2. When the shaft 15 and the cam disc rotate a certain arcuate amount, the ball is shifted out of the notch 54 and the spool 42 is correspondingly retracted to the position shown in Fig. 4, in which the ports are closed.

In operation, it will be seen that upon relative swinging of the main frame and tail boom in a vertical plane, the lever 21 will be correspondingly swung or rocked about the shaft 20. The yoke 19 will also be swung and the sleeve 16 will be moved up or down the shaft 15. This will cause the rocker arm 25 to turn on its shaft 26, thus shifting the spool 29 of the servo valve in one direction or the other so as to successively uncover one set or the other of the ports 34.

The fluid is thus free to flow between either chamber 31 or 32 and the chamber 44 of the lock valve sleeve and thence to or from rams 4 through passage 48 and the connected conduits of the hydraulic system, through port 37, chamber 33, port 49, chamber 44, and ports 47 and 46.

This flow is on the assumption that the lock valve is open, as is the case when the ball 52 is seated in the cam notch 54, and the land 50 of the spool 42 is shifted toward the shaft 15 to uncover the ports 47. This condition will obtain while the frame and tail boom of the leveler are in longitudinal alinement, and also with a relative rotation of the frame and tail boom about a vertical axis an amount insufficient to rotate the cam disc so as to entirely retract the ball 52 from the cam notch 54. The rams can thus be actuated even though the tail boom may be out of line to a relatively small degree.

When the ball is completely clear of the cam notch, however, the spool 42 is shifted so as to completely cover the ports 47, as shown in Fig. 4. As long as the spool is in this position therefore, the flow of fluid to or from the rams is completely shut off, regardless of any movement of the spool 29 of the servo valve.

The use of a number of separate small ports 34 in each set, practically overlapping each other in a direction axially of the spool, has been found to give a better and more sensitive flow control than is the case when a single elongated port is used.

It will be noted that the housing, including the dome, forms an oil-tight enclosure, so that all parts therein are protected and may be kept submerged in oil so that wear is reduced to a minimum.

It will also be observed that the construction and arrangement of parts within the housing is such that no adjustments of any such part is ever necessary.

From the foregoing description it will be readily seen that there has been produced such a device as will substantially fulfill the objects of the invention, as set forth herein.

While this specification sets forth in detail the present and preferred construction of the device, still in practice such deviations from such detail may be resorted to as do not form a departure from the spirit of the invention, as defined by the appended claims.

Having thus described the invention, the following is claimed as new and useful, and upon which Letters Patent are desired:

1. An actuator for the hydraulic level control rams interposed in the conduit system of a land leveler, said actuator comprising a housing adapted to be mounted on the leveler and including a fixed lower member and a dome mounted on said member for rotation about a vertical axis, a shaft concentric and fixed with the dome depending into the lower member of the housing, a rearwardly projecting lever pivoted on the dome for swinging movement in a vertical plane and turnable as a unit with the dome about said vertical axis, a sleeve slidable on the shaft, means between the lever and sleeve to shift the latter along the shaft upon swinging of the lever in a vertical plane, a servo valve in the lower member of the housing and adapted to be interposed in the conduit system to control the flow of fluid to and from the rams, means between the sleeve and servo valve to actuate the latter upon vertical movement of the sleeve, a normally open lock valve mounted in the lower member of the housing and adapted to be interposed in the conduit system between the servo valve and the rams, and means between the shaft and lock valve to close the latter upon rotation of the shaft a predetermined arcuate amount.

2. A structure, as in claim 1, in which the servo valve includes an axially movable spool disposed in a plane at right angles to the shaft and said actuating means comprises a generally L-shaped rocker arm disposed in the housing in a vertical plane, a transverse pivot support for the rocker arm intermediate its ends, the arm below the support being substantially vertical, an enlarged head on the lower end of the sleeve, the upper end of the rocker arm engaging the head, and a pivot connection between the lower end of the rocker arm and one end of the spool.

3. A structure, as in claim 2, in which the rocker arm engages the under side of the head, and a spring acting on the spool tending to shift the same lengthwise in a direction to maintain the rocker arm in contact with the head.

4. A structure, as in claim 1, in which the lock valve includes an axially movable spool disposed radially of the shaft, and a spring urging the spool toward the shaft; the valve closing means comprising a cam disc on the shaft disposed in the horizontal plane of the spool, said disc having a peripheral notch therein, and a noncompressible element engaging the end of the spool adjacent the

disc and seated in said notch when the valve is open and disengageable from the notch upon rotation of the disc so as to cause an axial movement in a valve closing direction to be imparted to the spool.

5. A structure, as in claim 4, in which the element is a ball, with retaining means for the ball included with the valve to prevent lateral and vertical shifting of the ball.

6. A structure, as in claim 4, in which the element is a ball, and the notch is of wide-angle V-form.
